CLAIM

The ornamental design for a combination flat hose and
reel cassette frame therefor, as shown and described.

DESCRIPTION

FIG. 1 is a perspective view from above of a combination
flat hose and reel cassette frame therefor showing
the front and the handle side of our new design;
FIG. 2 is an elevational view of the side opposite the
side shown in FIG. 1;

FIG. 3 is an elevational view of the handle side shown
in FIG. 1;

FIGS. 4 and 5 are respectively front and rear eleva-
tional views thereof; and,

FIGS. 6 and 7 are respectively top and bottom plan
views thereof.

FIG. 1

FIG. 2

FIG. 4

FIG. 3

FIG. 5

FIG. 6

FIG. 7
